[57] ABSTRACT

A pair of opposed ratchets are mounted for reciprocation along a predetermined path, and a pawl alternately engages each ratchet along its entire length. The pawl prevents reversal of direction of the ratchets until the path in each direction has been traversed. A set of channels guides the relative movement of the pawl and ratchets through a sequence of paths to effect the operation of the mechanism.

RECIPROCATING RATCHET MECHANISM

CROSS-REFERENCES TO RELATED APPLICATIONS

Reference is made to commonly assigned copending U.S. Patent application Ser. No. 46,856, entitled "Mechanism for Use in a Camera for Exposing and Initiating the Processing of Photographic Units," filed in the name of Leonard Kamp on even date herewith.

BACKGROUND OF THE INVENTION

1. Field of the Invention

This invention relates to reciprocating mechanisms having means for preventing reversal of direction only after a prescribed path has been traversed. More particularly, the present invention relates to pawl and ratchet mechanisms which permit reciprocating movement of a driven member, but with path reversal possible only when the pawl mechanism reaches a predetermined position on the ratchet mechanism.

2. Description of the Prior Art

Existing pawl and ratchet mechanisms which prevent reversal of the direction of travel of a reciprocating member prior to completion of a predetermined path of travel, generally comprise one or more pawl devices for engaging a single ratchet. In order to provide for reversal of the direction of travel of the pawl relative to the ratchet, a space must be provided at the end of the ratchet to permit the pawl device to be adjusted, such as by flipping over, to engage the ratchet in such a fashion as to prevent travel in the old direction while permitting travel in a new direction. A small of overtravel of the pawl carrier relative to the ratchet in each direction must be provided in such prior art systems to make reversal of direction of the carrier possible. This overtravel results in objectionable "play" in the carrier at the ends of the path. Furthermore, prior mechanisms of this type necessitate interruptions in the teeth at both ends of the ratchet, thus increasing the length of the ratchet relative to the length of the path of the pawl carrier.

SUMMARY OF THE INVENTION

The present invention provides a simple device including a reciprocating member, and means for preventing reversal of direction of the member prior its transversal of a predetermined path. In a preferred embodiment of the present invention, a pair of ratchets are carried by a slide in an opposed, parallel relationship, and they box in a pawl. The slide is reciprocatively displaceable relative to the pawl, the pawl being urged into engagement with alternate ratchets for respective directions of travel. The slide is sequentially guided along its path of travel relative to the pawl by a set of channels. Upon reaching a predetermined position relative to the slide, the pawl is disengaged from one ratchet and moved into engagement with the other ratchet and moved into engagement with the other ratchet to permit return travel of the slide.

An object of the present invention is to provide an improved reciprocating ratchet mechanism which is simple and compact.

Another object of the present invention is the provision of a reciprocating pawl and ratchet mechanism wherein a pawl is engaged with a ratchet throughout the reciprocating movement, and wherein overtravel for direction reversal is prevented.

Still another object of the present invention is the provision of a mechanism of the type described which is easy to operate. The invention, and its objects and advantages, will become more apparent in the detailed description of the preferred embodiment presented below.

The invention is especially suitable for use in a camera which effects both the exposure and processing of slide transparencies, such as that disclosed in commonly assigned U.S. Application Ser. No. 675,597, now U.S. Pat. No. 3,541,937 entitled "Camera and Method for Exposing and Developing Slide Transparency Units," filed in the name of Hubert Nervin on Oct. 16, 1967, wherein photographic units are suc-

sively drawn from a supply chamber to an exposure chamber, and exposed units are successively processed and pushed out of the camera. The invention is also suitable for use in a camera wherein fresh film must be advanced by exactly a full frame to prevent either double exposures or unused segments of film between exposures. While these uses suggest themselves, one skilled in the art will readily recognize that the invention lends itself to any application wherein anti-reversal reciprocating movement is desired.

10 The invention, and its objects and advantages, will become more apparent in the detailed description of the preferred embodiment presented below.

BRIEF DESCRIPTION OF THE DRAWINGS

15 In the detailed description of the preferred embodiment of the invention presented below, reference is made to the accompanying drawing, in which:

FIG. 1 is a partially sectioned view of the back of a camera 20 wherein a slide carrying a ratchet mechanism according to the invention is shown at one end of its path of travel relative to an associated pawl mechanism;

FIG. 2 illustrates the camera of FIG. 1 with the slide at an intermediate point in one direction of its path of travel;

FIG. 3 is a section through the line 3—3 in FIG. 1;

FIG. 4 shows the camera of FIGS. 1 and 2 with the slide at the opposite end of its path from that shown in FIG. 1; and

FIG. 5 is a view of the interior side of the camera door employing the invention, and is taken at the line 5—5 in FIG. 3

DESCRIPTION OF THE PREFERRED EMBODIMENT

Because cameras are well known, the present description will be directed in particular to elements forming part of, or 35 cooperating more directly with, cameras in accordance with the present invention. Specifically, the description will be directed to cameras for exposing and processing photographic units, such as that disclosed in above-cited U.S. Application Ser. No. 675,597 now U.S. Pat. No. 3,541,937. It is to be understood that camera elements not specifically shown or 40 described may take various forms well known to those skilled in the art.

Referring to FIGS. 1 and 3, the interior of the door of a 45 camera 1 includes a latch 2 having a pair of slots 4 through which studs 6 extend from camera 1 to permit limited vertical movement of the latch. Latch 2 includes a lug 8 which is shown engaged in a slot 10 on a slide 12. Latch 2 also carries a pawl 14 which is mounted on a pivot 16. Latch 2 is urged upward by a torsion spring 18. Slide 12 includes a pair of opposed, parallel ratchets 22 and 24. A surface 20 of pawl 14 is urged by a torsion spring 19 on latch 2 into engagement with the first of teeth 21 in ratchet 22. Latch 2 has a numeral "1" and an arrow provided thereon which indicated that depression of latch 2 by a button 3 is the first step in a sequence of 50 operational steps to be described subsequently.

Also shown in FIGS. 1 and 3 is a handle 26 which, when moved to the right as directed by the numeral "2" and the accompanying arrow, urges slide 12 to the right. The latter directional figures are embossed on a bearing plate 13 for slide 60 12 mounted on the camera beneath the slide 12, and are visible through an opening in the camera casing. It will be observed that the depression of button 3 urges lug 8 out of slot 10 and into contact with the top of a thin spring 28, and that the subsequent movement of button 26 to the right causes the irreversible movement of slide 12 and the parts included 65 thereon to the right.

Slide 12 further includes slots 30 and 32 which are parallel to ratchets 22 and 24. When latch 2 is moved downward and 70 slide 12 is urged to the right as described above, spring 28 guides lug 8 into slot 30. The position of pivot 16 is such that when lug 8 travels in slot 30, surface 20 of pawl 14 is maintained in engagement with the teeth 21. Thus, in FIG. 2, slide 12 is shown at an intermediate point in its path of travel with lug 8 engaged in slot 30, and surface 20 of pawl 14 engaged in 75

teeth 21 of ratchet 22. Also, the movement of slide 12 to the right causes the concealment of the instructional numeral "4" carried on a part of slide 12 previously covered by the camera casing.

As slide 12 is urged to the right, lug 8 eventually reaches the end of slot 30 and enters notch 29 at the end of slots 30 and 32. A numeral "3" with an accompanying arrow printed on a depression 33 is a portion of the camera casing which was initially concealed by button 3, and which was displayed upon the depression of latch 2 in the first step, indicates that the third operational step requires the further depression of latch 2 by means of button 3. This forces lug 8 under a thin spring 34 as shown in FIG. 4. In addition, as pawl 14 is disengaged from teeth 21 with the depression of latch 2, it is subjected to the counterclockwise force of spring 19, and surface 36 of pawl 14 is thus put in engagement with teeth 38 of ratchet 24. The subsequent irreversible movement of slide 12 to the left as instructed by numeral "4" causes lug 8 on latch 2 to travel along slot 32 while pawl 14 is maintained in engagement with teeth 38 of ratchet 24. When the leftward path of travel is completed, lug 8 leaves slot 32. Spring 18 urges latch 2 upwardly, lug 8 is moved past spring 28 into notch 10. The mechanism has returned to the initial arrangement depicted in FIG. 1. It should be noted that when lug 8 is moved past springs 34 and 28 respectively, lug 8 cannot be moved past those elements causes them to obstruct such reverse movement.

When incorporated in a camera according to previously reference copending U.S. Application Ser. No. 675,597, now U.S. Pat. No. 3,514,937, Ser. No. 46,856, the ratchet mechanism is used to effect the reciprocation of carriage 40 shown in FIGS. 3 and 5. Carriage 40 comprises a claw assembly 42 for engaging and transporting fresh photographic units from a storage chamber to an exposure chamber in the main body portion of camera 1, and a roller assembly 44 for rupturing pods of processing solution carried by the units to effect the processing of exposed units. The claw and roller assemblies are mounted on a resilientember 46 which is attached to the forward side of slide 12 by means of screws 48, the exterior of the door being considered the back of the camera. Carriage 40 is successively reciprocated in a path across the inside of the camera door to accomplish its functions. Accordingly, after an exposure has been made, the photographer depresses the button 3 and moves handle 26 to the right (FIG. 2) to move slide 12, hence carriage 40, to the left (FIG. 5) to rupture a pod on an exposed photographic unit and, at the end of the initial direction of travel, to engage a fresh unit. Button 3 is then depressed further and handle 26 is moved to the left (FIG. 4), to drive carriage 40 to the right (FIG. 5), thereby taking a fresh unit to the exposure area and pushing the exposed transparency through an exit in the camera (not shown).

The invention has been described in detail with particular reference to the preferred embodiment thereof, but it will be understood that variations and modifications can be effected within the spirit and scope of the invention.

I claim:

1. A reciprocating ratchet mechanism comprising:

a pawl mechanism;

a member mounted for reciprocating movement relative to said pawl mechanism in first and second directions between first and second end positions, said member including first and second opposed ratchets, said pawl mechanism being alternately movable into engagement with said first and second ratchets when said member moves in said first and second directions respectively, to prevent said member from changing its direction of travel at a position between said end positions;

control means for maintaining said pawl mechanism in engagement with said first ratchet during movement of said member in said first direction, for maintaining said pawl mechanism in engagement with said second ratchet during movement of said member in said second direction, and for permitting movement of said pawl mechanism

between engagements with said first and second ratchets at said end positions.

2. A reciprocating ratchet mechanism comprising:

a housing;

a member mounted in said housing for reciprocating movement in first and second directions along a path from a first end position to a second end position, and back to said first end position, respectively, said member including said first and second ratchets;

pawl means for controlling movement of said reciprocable member, said pawl means including first and second pawl surfaces, said first pawl surface being engageable with said first ratchet to prevent movement of said reciprocable member in said second direction while permitting movement of said member in said first direction, and said second pawl surface being engageable with said second ratchet to prevent movement of said reciprocable member in said first direction while permitting movement of said member in said second direction;

pawl control means mounted in said housing and coupled to said pawl means for movement transverse to said first and second directions between a first control position in which said first pawl surface is in engagement with said first ratchet, and a second control position in which said second pawl surface is in engagement with said second ratchet; and

guide means carried by said reciprocating member for controlling the transverse movement of said pawl control means, wherein said guide means defines a path for said pawl control means between said first and second control positions in response to movement of said reciprocating member to said end positions, and for maintaining said control means in said first and second control positions during movement of said reciprocating member in said first and second directions, respectively.

3. In a camera for exposing and initiating the processing of photographic units and including a carriage reciprocable between first and second positions in the camera for transporting photographic units in the camera, a mechanism for operating the carriage, said mechanism comprising:

a. a slide, reciprocable between said first and second positions along a first path;

b. a latch, reciprocable between third and fourth positions along a second path transverse to said first path;

c. means for preventing reversal of the direction of travel of said slide at a point between said first and second positions, said means comprising:

a pair of opposed ratchets carried by said slide and having a length equal to the distance between said first and second positions;

pawl means carried by said latch for engaging one of said ratchets when said slide is between said first and second positions;

a pair of adjacent channels, each parallel with a corresponding ratchet, carried by one of said slide and latch, and end channels connecting adjacent ends of said channels and delimiting said channels to a length corresponding to that of said ratchets;

a lug carried by the other of said slide and latch, for engaging said channels and end channels and moving along the length thereof;

wherein said channels and lug are positioned on said slide and latch relative to said pawl and ratchets to maintain said pawl means in engagement with alternate ratchets when said lug is engaged with alternate channels.

4. A mechanism according to claim 3 wherein:

said ratchets are parallel, said channels and end channels are carried by said slide, and said channels parallel with said ratchets;

said lug is carried by said latch; and

said pawl means comprises:

a pawl having two opposite end portions for engaging respective ratchets, said pawl being pivotally

mounted on said latch at a position intermediate said end portions, and means for urging respective end portions into engagement with a corresponding one of said ratchets when said lug is engaged with the channel corresponding to said corresponding ratchet.

5. A mechanism according to claim 4 further comprising means for urging and guiding said latch to a fifth position in which said lug assumes a position blocking said slide from movement and retains said slide in said first position.

6. A mechanism according to claim 5 further including: means for moving said latch from said fifth position to said third position wherein said lug is in alignment with a first of said channels; means for moving said slide from said first position towards said second position, such that said lug is engaged with said first channel, and a first of said pawl end portions is

engaged with a first of said ratchets, which ratchet corresponds to said first channel, and for moving said slide from said second position towards said first position, such that said lug is engaged with said second channel and the second of said pawl end portions is engaged with the second of said ratchets, which ratchet corresponds to said second channel; and

means for moving said latch to said fourth position and for moving said lug along the second of said end channels, in which fourth position said lug is in alignment with the second of said channels.

7. A mechanism according to claim 6 further comprising means responsive to the movement of said latch to said fourth position for preventing said latch from returning to said third position.
